UNITED STATES PATENT OFFICE.

MICHAEL J. BRIERTY, OF CHICAGO, ILLINOIS.

HEAT-CONTROLLING APPARATUS.

No. 902,936.

Specification of Letters Patent.

Patented Nov. 3, 1908.

Application filed January 20, 1908. Serial No. 411,715.

To all whom it may concern:

Be it known that I, MICHAEL J. BRIERTY, a citizen of the United States, residing at Chicago, in the county of Cook and State of Illinois, have invented a new and useful Improvement in Heat-Controlling Apparatus, of which the following is a specification.

My invention relates particularly to heat-controlling apparatus having an electric-controlling circuit; and my primary object is to provide improved electrically-controlled means for regulating the temperature of the atmosphere in a room or the like.

My invention is illustrated in the accompanying drawings, in which—

Figure 1 shows by a vertical sectional view a building supplied with a heater or furnace equipped with draft and "check" doors or dampers controlled by my improved apparatus. Fig. 2 is a similar view of a room equipped with a radiator for furnishing heat to it, the admission of the heating medium to the radiator being shown as controlled by my improved apparatus. Fig. 3 is a section taken at the line 3 on Fig. 2 and viewed in the direction of the arrow, showing the radiator in plan; and Fig. 4 is a view of my improved apparatus in elevation, with its enveloping case removed, together with a thermometer represented in circuit with the apparatus for controlling the operations of the latter.

My improved apparatus is designed to be used preferably in conjunction with a circuit-making-and-breaking thermometer whereby electrical connections with the apparatus may be established and broken under the influence of changes in temperature of the atmosphere surrounding the thermometer, and thus the source of heat-supply be regulated to maintain approximately even temperature.

My improved apparatus 5 comprises a base 6, an electric motor 7 secured to the base and provided on its armature-carrying shaft 8 with a pinion 9 which meshes directly with the gear 10 of a train of gears 11, 12, 13, 14, 15 and 16, suitably journaled in uprights 17 (one only of which is shown) secured on the base 6, the arbor 18 of the gear 16 of the train carrying a crank-arm 19 and a commutator 20 containing a segment 21 of insulating material. The apparatus further comprises brushes 22, 22^a, which preferably are pivoted as indicated at 23 between their ends between the ears 24 of a

cross-member 25 preferably of insulating material extending between the two uprights 17, the brushes 22 being caused to bear against the commutator 20 through the medium of adjusting screws 26 working through the upper ends of the brushes 22 and against the cross-member 25; and a relay 27. The relay comprises an electromagnet 28 provided with heads 29, 29, preferably of insulating material and supported on the base 6 as through the medium of a metal plate 30; a contact-bar 31 mounted in an upright 32 secured to the plate 30 preferably formed of insulating material; a metallic arm 34 pivoted at its lower end to ears 35 on the plate 30 to be swung back and forth into and out of engagement with the contact 31 and a contact 36, which may be secured to the adjacent head 29, as shown; and a spring 37 fastened to the upper contact-member 38 of the arm 34 and to an eye 39 of insulating material carried by the contact-bar 31 and serving to normally hold the arm 34 against the contact 31. The gears of the train are preferably so constructed and arranged that the ratio of movement between the pinion 9 and arbor 18 is about 400 to 1, whereby, upon rotating the motor as hereinafter described, the arbor 18 rotates very slowly, but affords relatively great power.

In Fig. 1, the apparatus 5 is shown as applied to a furnace 40 located in a basement and supplying heat to a room above it. The furnace illustrated has a check-door 41 and a draft-door 42 connected together by a chain 43 extending over pulleys 44, 44, the length of the chain 43 being such as to cause one door to be open when the other is closed. The apparatus 5 is shown as supported from a bracket 45 with its crank-arm 19 connected with the chain, as indicated, at 46 for drawing the latter up and down and opening and closing the doors 41 and 42, as hereinafter described. The room above the basement is shown to contain an electric thermometer 47 which may be of any suitable type, the one shown in Fig. 4 being the one desired and comprising three contact-points 48, 49 and 50 extending into the path of the mercury contained in the bulb 51 and tube 52 of the thermometer, and connected through wires 53, 54 and 55 to buttons 56, 57 and 58 respectively; and a switch 59 adapted to be swung into engagement with any one of the buttons.

The electrical connections between the parts described and the thermometer are as follows: Wires 60 and 61 connect the brushes 22 and 22^a with the contact 36 and contact 31, respectively. A wire 63 leads from the commutator 20 to one of the brushes of the motor 7, the connections of the motor being such, as is well understood in the art, to constitute the terminal 64 of the field magnet 10 65 of the motor the other connection for the motor, this terminal 64 connecting with an electrode 66 of one of a set of two batteries 67 and 68 through the medium of a wire 69. The terminals 70 and 71 of the coil 28 connect 15 respectively with a binding-post 72, also serving as a binding-post for the arm 34 by reason of its metallic connection therewith, and with the switch 59 of the thermometer, through the medium of wires 73 20 and 74 respectively, a wire 75 connecting the binding-post 72 with an electrode 76 of the cell 68. A wire 77 connects the other electrode 78 of the cell 67 with the other electrode 79 of the cell 68, and a wire 80 connects the 25 mercury in the bulb 51 of the thermometer with the electrode 78 of the cell 67.

The operation of the apparatus is as follows: Assuming the switch 59 of the thermometer to be in contact with the button 57 30 and the mercury in the bulb and tube 51 and 52 to have just made connection with the contact 49, as illustrated, a circuit is established through the battery, wire 80, thermometer 47, wire 74, magnet 28^a and wires 73 and 75, thereby energizing the magnet and causing the arm 34 which constitutes the armature for the magnet, to be swung from the position illustrated in Fig. 4, into engagement with the contact 36, against the 35 resistance of the spring 37, thereby establishing the following circuit: The current passes from the battery through the wire 75, binding-post 72, plate 30, the armature 34 and contact 36; thence through the wire 60 40 to the brush 22; thence through the brush, the commutator 20 and wire 63 to the motor 7; through the motor, and from the motor through the wire 69 to the battery thus completing the circuit through the motor. The 45 circuit thus established through the motor immediately causes it to operate, the motor continuing to run until the commutator 20 has been turned about one-half a revolution, thereby carrying the segment 21 of insulating material from the position illustrated in 50 Fig. 4 in contact with the brush 22^a, into contact with the brush 22 with the effect of breaking the circuit through the motor and thus stopping it. The turning of the arbor 55 18 and commutator 20 about one-half a revolution as described, causes the crank 19 to be turned from the upwardly extending position illustrated in Fig. 4 to a depending position, which thus causes the draft-door 42 to be closed and the check-door 41 to be

opened. It will be understood that as long as the mercury in the tube 52 remains in contact with the contact 49, a current passes through the magnet 28^a and the armature 34 remains in engagement with the contact 36. 70 As soon as the mercury drops below the contact 49 the circuit through the magnet 28^a is broken and the armature 34, under the influence of the spring 37, is caused to be swung to the position illustrated in Fig. 4 75 in which it engages with the contact 31. As soon as this occurs, the circuit is established through the battery, wire 75, plate 30, armature 34, contact 31, wire 61, brush 22^a, commutator 20, wire 63, motor 7 and wire 80 80 69 to the battery, thus establishing a new circuit through the motor. The motor is thus caused to again operate, and in the same direction as before, and it continues to run until the segment 21 is brought into contact with the brush 22^a, whereupon the circuit is again broken through the motor. The operation just described causes the 85 crank-arm 19 to return to the position illustrated in Fig. 4 with the result of opening 90 the draft-door 42 and closing the check-door 41, as illustrated in Fig. 1. Succeeding operations of the apparatus are repetitions of those just described, the magnet being energized when the temperature in the room 95 reaches that desired to close the draft-door and open the check-door, and deenergized to reverse the operation when the temperature of the atmosphere drops below that desired.

In the arrangement illustrated in Fig. 2, 100 my improved apparatus is designed to control the admission of a heating medium, such as steam or hot water, into a radiator 81 under variations of temperature in the room 82 in which it is located, through the 105 medium of a thermometer as described. As shown, the crank-arm 19 of the apparatus 5 connects with a crank-arm 83 on the admission valve 84 of the radiator 81, whereby, in the operations of the apparatus as described, 110 the crank-arm 19 is moved one-half a revolution to open the valve 84 and the other half to close it under the influence of electrical circuits established through the apparatus 5 as described. 115

From the foregoing description it will be readily understood that the construction of my apparatus is such as to render its operation reliable and accurate and very sensitive to changes in temperature. 120

What I claim as new, and desire to secure by Letters Patent, is—

1. The combination with a source of electro-motor force, of an electric motor, a driven shaft, gear-connection between the motor and shaft, a make-and-break device constructed and arranged to make and break circuit under changes in the temperature of the atmosphere surrounding it, an electro-magnet in circuit with said make- 125 break device, and a crank-arm 130

and-break device, a set of electrical contacts insulated from each other, an armature for the magnet suitably pivoted near its lower end to adapt it to be swung back and forth 5 into alternate engagement with said contacts, means for yieldingly holding said armature in engagement with one of said contacts, and means in circuit with said contacts and the motor for maintaining the current through the latter during the turning 10 of the shaft a predetermined distance while the armature remains in unchanged conditions.

2. The combination with a source of electro motor force, of an electric motor, a driven shaft, gear connection between the motor and shaft, a contact - making - and - breaking device constructed and arranged to make and break circuit under changes in the 15 temperature of the atmosphere surrounding it, an electro-magnet in circuit with said make-and-break device, an armature for the magnet operated against an end thereof and constructed and arranged to be normally out 20 of contact therewith, a set of electrical contacts with which the armature is adapted to alternately and bodily engage, and means in circuit with said contacts and the motor for maintaining the current through the motor 25 during the turning of the shaft a predetermined distance while the armature remains in unchanged condition.

3. The combination with a source of electro motor force, of an electric motor, a driven shaft, gear connection between the motor and shaft, a commutator carried by the shaft and containing a section of insulating material, brushes engaging with the commutator, an electrical contact - making - and - breaking device constructed and arranged 35 to make and break circuit through it under

changes in the temperature of the atmosphere surrounding it, an electro-magnet in circuit with said make-and-break device, a set of electrical contacts in circuit with the 45 brushes, the commutator and motor, and an armature for the magnet operating against an end thereof and constructed and arranged to alternately and bodily engage 50 with the contacts of said set and direct the current from said source through the brushes alternately and through the commutator and motor, for the purpose set forth.

4. The combination with a source of electro motor force, of an electric motor, a driven shaft, gear connection between the motor and shaft, a commutator carried by the shaft and containing a section of insulating material, brushes engaging with the commutator, an electrical contact-making- 55 and-breaking device constructed and arranged to make and break circuit under changes in the temperature of the atmosphere surrounding it, an electro-magnet in circuit with said make-and-break device, a 60 set of electrical contacts insulated from each other and in circuit with the brushes, commutator and motor, an armature for the magnet suitably pivoted near its lower end to adapt it to be swung back and forth 65 into alternate engagement with said contacts and direct the current from said source through the brushes alternately and through the commutator and motor, and means for yieldingly holding said armature away from 70 the magnet and in engagement with one of said contacts, for the purpose set forth.
